UNITED STATES PATENT OFFICE.

CHARLES D. LANNING, OF BOSTON, MASSACHUSETTS.

ELECTROMAGNETIC DEVICE FOR ALTERNATING CURRENTS.

1,002,712.

Specification of Letters Patent. Patented Sept. 5, 1911.

Application filed August 2, 1910. Serial No. 575,051.

To all whom it may concern:

Be it known that I, CHARLES D. LANNING, a citizen of the United States, and a resident of Boston, in the county of Suffolk, 5 State of Massachusetts, have invented an Improvement in Electromagnetic Devices for Alternating Currents, of which the following description, in connection with the accompanying drawings, is a specification, 10 like letters on the drawings representing like parts.

This invention relates to electro-magnetic devices, more particularly to those intended to be energized by alternating currents, and 15 has particular reference to improvements in the efficiency of electro-magnets which are energized by alternating currents, and particularly those of relatively slight strength and high frequency, such, for example, as 20 telephonic currents or the like.

My invention will be best understood by reference to the following description when taken in connection with the accompanying illustration of one specific embodiment 25 thereof, while its scope will be more particularly pointed out in the appended claims.

In the drawings: Figure 1 represents diagrammatically a circuit arrangement, 30 embodying one form of my invention; Fig. 2 is a plan view of a switch which may be employed in the arrangement shown in Fig. 1; Fig. 3 is a central section in elevation, partially broken away, and on an enlarged scale, showing the construction of the 35 switch disclosed in Fig. 2; and Fig. 4 is a detail of the connection between the switch arm and its controlling spring.

Referring to Fig. 1 of the drawings, I 40 have there illustrated one form of my invention applied to a telephone system, and to an instance where it is necessary to control a switch or other device by means of a magnet energized by the voice-caused alternating currents on the telephone line. In 45 this particular instance the telephone circuit is provided with a repeating station having circuit-changing means for establishing repeating relations between the sending and receiving station, such circuit-changing means being controlled by a voice-energized electro-magnet.

Referring to the diagrammatic showing in Fig. 1, there is conveniently represented 55 at 1 a telephone station which may be adapted both for the transmission and the receipt

of telephonic currents, such station being connected with the repeating station by the line circuits 2 and 3. The line 2 is split into two branches 4 and 5, the former passing 60 through the primary of the transmitting induction coil 6, and thence through the primary of the switch controlling induction coil 7 to the switch contact 8. The latter is normally engaged by the pivotally mounted 65 switch 9, the latter being maintained in such position by the spring or other restoring member 10. The other branch 5 of the circuit 2 forms a receiving circuit leading to the secondary of the receiving coil 11, and 70 thence to the normally opened switch-controlled contact 12 at the switch 9. The opposite side 3 of the transmitting circuit is permanently connected to the controlling switch 9 by any suitable means as, for example, through the restoring spring 10. While the switch 9 normally engages the contact 8, it may be withdrawn therefrom and moved to engage the contact 12 on energization of the switch-controlling electro- 75 magnet 13.

Referring now to the sending and receiving station 14 at the opposite end of the line, the main circuits 15 and 16 lead to the repeating station and have connections corresponding generally to those already described, which it will not be necessary again to enumerate, there being provided, however, for these circuits a controlling switch 17 similar to the switch 9, switch contacts 18 and 19, a switch-operating magnet 20 and a restoring spring 21.

It will be seen that in the normal state of the apparatus, with the magnets deenergized, the connections remain as shown in the diagram. In the arrangement shown I rely upon the initially transmitted voice-caused telephone currents to energize the proper magnet and throw the switch to make the requisite repeating connections. 100 To energize the proper magnet, each magnet is connected in series with the secondary of its switch-controlling induction coil, and, to secure the best results, I have made special provision for rectifying the alternating currents which pass from the coil to the magnet, thereby providing a uni-directional magnetizing current. To this end the magnet winding 22 has interposed between it and the induction coil a suitable rectifying 105 element, such as an asymmetrical cell 23, the well-known property of which is to

prevent the current from passing in one direction while permitting it to pass in the opposite direction. Such asymmetrical element may be provided in any desired form, as, for example, in the form of a cell having lead and aluminum electrodes immersed in an alkaline electrolyte such as a sodium ortho-phosphate solution. Such an asymmetrical cell when placed in an alternating current circuit offers very little resistance when the current passes in at the lead electrode and out at the aluminum electrode; but when the current is reversed it meets with a heavy resistance due to a thin film of non-conductive oxid which instantly forms on the surface of the aluminum. The asymmetrical cell, therefore, in series with the magnet winding 22, provides for a unidirectional current therethrough consisting of the successive half alternations or current impulses of the same sign or directional character. To utilize the reverse alternating impulses for energizing the magnet, the latter is also provided with a second parallel winding 24 which is also connected in series with the secondary of the induction coil 7, but in a separate branch circuit from the winding 22 and having serially related thereto another asymmetrical element, such as the asymmetrical cell 25. The two magnet windings 22 and 24 are so connected through their respective asymmetrical elements to the terminals of the induction coil secondary that they tend to reinforce each other and establish each a magnetic field of the same polarity. It therefore follows that, in each alternating current cycle, the cessation of the decreasing magnetizing current in one circuit is immediately succeeded by the flow of an increasing magnetizing current in the other circuit, having the same direction and magnetizing effect. This not only provides against reversal in the magnet current but actually leaves no interval of de-magnetization, for, at the neutral point, *i. e.* when theoretically, between the two pulsations there is no current, the magnet still tends to attract the switch through the residual or remainant magnetism.

Turning again to the circuit connections in Fig. 1, the effect of throwing the switch 17, by means of the voice currents transmitted from the station 1, is to interrupt the transmitting circuit from the station 14, through the branches 26 and 27, at the contact 18 and to complete the receiving circuit passing thereto through the branches 28 and 29. Under such conditions the voice currents generated at the station 1 are reproduced in the receiving circuit of the station 14 through the interposition of suitable repeating devices. For this purpose, there is interposed between the primary of the

transformer 6, which is in the branch 4 of the main line circuit 2, and the secondary of the transformer 30, which is in the receiving branch 28 of the main line circuit 15, a repeater 31 which I have shown in conventional diagrammatic form, but which may be of any design or construction adapted to reproduce accurately, and preferably with increased intensity, the electrical undulations of the circuit 2-3, again in the secondary of the transformer 30. This repeater herein shown consists of a magnet coil in circuit with the secondary of the transformer 6 and having an armature adapted to vary the pressure in a suitable form of carbon or microphonic contact, thereby varying the current flowing in the primary of the transformer 30. With the switch 17, therefore, in the dotted line position shown, undulations in the circuit 2-3 are thus reproduced in the secondary of the transformer 30 and transmitted to the main line circuit through the branch or receiving circuits 28, 29, and thus to the distant station. At the same time the transmitting circuit on the lines 26-27 being open at the switch, the associated transmitting apparatus for station 14 is, therefore, unaffected by any energy subsequently transmitted over the line 2-3 from the station. As soon as transmission of voice energy from the station 1 ceases, the magnet 20, being thereupon deenergized, the switch 17 is restored by the spring 21 to the position shown in full lines, breaking from the receiving branch 28 for the station 14 and again completing the circuit for the transmitting branches 26, 27 thereof, leaving the repeater in condition again to pass under the control of the next voice currents to pass over the line. If voice energy is transmitted from the station 14 to the station 1 the transmitting branch for the station 1 is immediately broken by the movement of the switch 9, which at the same time completes the receiving branch thereof and the voice energy from the line 15, 16 is reproduced with intensification in the line circuit 2-3, through the repeater 32, all of which will be readily understood from the foregoing description. The circuit control is, therefore, automatically effected by the telephone currents themselves, the switch corresponding to that terminal station toward which the voice energy is transmitted, being instantly thrown, through the medium of its controlling electro-magnet, to break its transmitting circuit and place its receiving circuit in condition to receive and pass on the voice-actuated currents.

It will be observed that the asymmetrical cells 23 and 25 are not in the main telephonic circuit but that the circuit containing the same is inductionally related to the main line circuit so that the telephonic currents

do not actually pass through these cells and the main telephonic line circuit cannot be affected by any variations in resistance of the asymmetrical elements.

5 In the control of a switch, such as described, by means of an electro-magnet energized through alternating currents, as, for example, telephone currents, it is ordinarily necessary to provide a spring or other restoring member, having a low rate of vibration which, in the case of telephone currents, should be less than the lowest audible tone of the human voice. Otherwise the reversal 10 in the magnetizing current of the magnet 15 will, at the zero point of magnetism, tend to release the switch and allow the spring to restore the same to its normal position, so that the alternations of current will tend to induce a sympathetic vibration in the spring 20 instead of holding the switch steadily attracted during the alternating passage of the current through the magnetic coils. In a magnet wound and energized as described, however, the precaution of an abnormally 25 low period of vibration for the spring is unnecessary, since the switch will remain attracted by the magnet so long as the restoring force of the spring is less than the remainant magnetism which is effective between the succeeding uni-directional pulsations. Furthermore, since there is no reversal of the magnetizing current, a more effective magnetism is secured from a given 30 strength of alternating current, which is particularly advantageous in the case of telephone currents and other weak currents, particularly those of high periodicity where self-induction and hysteresis losses are apt to be great.

40 In Figs. 2 to 4 I have illustrated the details of a controlling switch which may be employed in connection with a system like that described in Fig. 1. Referring to the drawings, the switch parts are mounted 45 upon a base 45 of insulating material. The switch arm 46 is a small piece of some light conductive material, preferably aluminum, which is shown drilled out further to lighten the same. The switch arm is delicately and 50 sensitively supported by a pivoted pin 47 mounted in jeweled cup bearings 48, so that it may execute the slight movement necessary with a minimum amount of friction and inertia. The upper bearing is shown adjustable by means of a thumb screw 49 and lock nut 50. The switch controlling magnet 51 is suitably supported upon a base to face a thin, light armature 52, preferably a piece 55 of soft, thin sheet iron secured to the end of the switch arm. The double or parallel windings of the magnetic coils are connected to the terminal binding posts 53, 54, 55 and 56 and are mounted upon the ends of the horse shoe core 57 as close to the armature 60 as possible. The core 57 is preferably of

soft laminated iron. The stationary contacts are shown in the form of adjustable screws 58 and 59 adjustably mounted in posts 60 and 61, and preferably tipped with platinum ends which coöperate with platinum contacts 62 upon the switch arm. The posts 60 and 61 are connected, respectively, to terminal posts 63 and 64. The switch arm 46 is normally held in contact with one of the contact screws (with screw 59 in Fig. 2) by means of a resilient restoring member, the same herein comprising a relatively long, fine, flexible wire 65 having one end resting in the V-shaped groove of an upturned ear 66 (see Fig. 4) on the rear end of the switch arm, and the opposite end held fixed in a block 67 which may be slightly adjusted transverse the axis of the wire in the fixed frame 68 by means of the fine differential adjusting screw 69. The wire 65 is preferably of iridium-platinum and so finely dimensioned as to exert a very delicate restoring tendency upon the switch arm. Connections may be made to the switch arm through the platinum wire 65, the sliding 70 block 67 and frame 68 by means of the lead wire 70 and the binding post 71. By adjusting the block 67, the restoring tendency of the spring may be adjusted.

To obtain the best results and maintain the switch in perfect balance, the base 45 is provided with the leveling screws 72 and the spirit level 73.

It will be understood that my invention is not limited to the particular details herein shown, either of construction, circuit arrangement or application of the invention, these being submitted for purposes of illustration only, but that extensive deviations may be made therefrom without departing from the spirit of the invention.

Having thus described my invention, what I claim is:

1. In a telephone relay system a two-way repeating device comprising one or more repeating instruments, circuit controlling means for establishing and maintaining the circuits to and from the repeating device according to the direction of sound transmission from the speaking to the listening station, an electro-magnet for actuating said circuit controlling means, said electro-magnet being energized through the voice-caused currents from the speaking station, and current rectifying means for providing a uni-directional current for the said magnet.

2. In a telephone relay system a two-way repeating device and a line circuit leading from each station thereto, said repeating device including a circuit-changing device for placing either station in suitable repeating communication with the other according to the direction of sound transmission, an electro-magnet actuated by the

voice currents in either line circuit for operating said circuit-changing device, parallel windings for said magnet, and an asymmetrical element associated with each winding for causing current impulses alternately through the two windings having a uni-directional magnetizing effect.

3. In a telephone relay system, a repeating station; terminal stations having line circuits leading to said repeating station; a transmitting circuit and receiving circuit for each line circuit at said repeating station; and means for automatically breaking the receiving circuit from one station and 15 making the corresponding transmitting circuit on the passage of voice currents from the opposite terminal station, said means comprising an electro-magnetic device energized by the said voice currents; and current rectifying means for providing therefrom the said voice currents, a uni-directional magnetizing current.

4. A telephone apparatus of the class described having means for reproducing telephonic speech, sounds or the like alternately 25 from one main line circuit into another main line circuit consisting of a telephone transmitter induction coil, a source of electro-motive force and circuit connections, electromagnetic apparatus responsive to the voice 30 caused currents originated at either sending station for automatically selecting or connecting the two main line circuits; and current rectifying means for providing from said voice caused currents uni-directional 35 magnetizing currents for said electromagnetic apparatus.

In testimony whereof, I have signed my name to this specification, in the presence of two subscribing witnesses.

CHARLES D. LANNING.
